Primary Examiner — Mary Ann Calabrese*Assistant Examiner* — Katelin G Kloberg(74) Attorney, Agent, or Firm — Cislo & Thomas, LLP(57) CLAIM

I claim the ornamental design for a vanity cabinet, as shown and described.

DESCRIPTION

FIG. 1 is a front perspective view of the vanity cabinet.

FIG. 2 is a front view thereof.

FIG. 3 is right side elevation view thereof with the left side elevation view being a mirror image thereof; and,

FIG. 4 is a bottom view thereof.

The broken lines shown in the drawings depict portions of the article and form no part of the claimed design.
